(57) **CLAIM**

The ornamental design for a bicycle wheel bag with herringbone pattern, as shown and described.

DESCRIPTION

FIG. 1 is a front perspective view of the bicycle wheel bag with herringbone pattern showing the present invention; FIG. 2 is a front view of the bicycle wheel bag with herringbone pattern, the rear view being a mirror image thereof; FIG. 3 is a right side view of the bicycle wheel bag with herringbone pattern;

FIG. 4 is a left side view of the bicycle wheel bag with herringbone pattern;

FIG. 5 is a top view of the bicycle wheel bag with herringbone pattern;

FIG. 6 is a bottom view of the bicycle wheel bag with herringbone pattern; and,

FIG. 7 is an enlarged fragmentary view of FIG. 2 showing the circled portion in FIG. 2.

The long broken lines illustrate the bicycle wheel bag with herringbone pattern's handle, zipper hardware, and body strap. The short broken lines illustrate stitching. The dash dot broken lines in FIG. 2 indicate the portion of the bag's surface shown enlarged in FIG. 7. None of the broken lines form part of the claimed design.
